DOUGHNUT HOLDER

George D. Herrick, Sr., 611 W. 11th St., Medford, Oreg.

Filed Apr. 8, 1960, Ser. No. 60,101

Term of patent 3½ years

(Cl. D44—10)

Fig-1

Figure 1 is a front elevational view of a doughnut holder, according to the present invention, showing my new design;

I claim:

The ornamental design for a doughnut holder, as shown.
